UNITED STATES PATENT OFFICE.

HENRY F. NEWBURY, OF NEW YORK, N. Y., ASSIGNOR TO ELEVATOR SUPPLY AND REPAIR COMPANY, A CORPORATION OF ILLINOIS.

SIGNAL APPARATUS.

1,100,767.

Specification of Letters Patent. Patented June 23, 1914.

Application filed November 28, 1904. Serial No. 234,356.

To all whom it may concern:

Be it known that I, HENRY F. NEWBURY, a citizen of the United States, residing in the borough of Brooklyn, city of New York, county of Kings, and State of New York, have invented certain new and useful Improvements in Signal Apparatus, of which the following is a full, clear, and exact description, reference being had to the drawings accompanying and forming a part of the same.

This invention relates generally to signal apparatus in which a person at a given point or station can cause a portion, normally in an inoperable condition, to move or be put into an operable condition and a signal to be given by the movement of a car or similar moving object as it approaches a given point and to restore the parts to their normal condition.

In the embodiments of my invention shown in the drawings, Figure 1 illustrates diagrammatically the circuits, their terminals, means for closing and opening such circuits and also the general construction of the system or apparatus by which the signals are given both in a car and at local stations to be served by such car, there being signal devices for giving such signals to two cars and the stations served thereby thus shown; Fig. 2 is a front view showing the switch devices, the means by which the movable parts are moved to bring the circuits from an inoperable to an operable condition, means by which such circuits are held or retained in operable condition and means by which such circuits are restored to an inoperable condition; Fig. 3 shows in longitudinal section on line 3—3, of Fig. 2, that which is shown adjacent to that line in this Fig. 2; Fig. 4 shows in cross section on an enlarged scale, line 4—4 of Fig. 2, the parts there seen; Fig. 5 shows in front view and partly in section some of the parts seen in Fig. 4; Fig. 6 shows one of the switch devices and connected parts seen at the right of Fig. 4; Fig. 6^a shows the same parts seen in Fig. 6 and with the movable parts in the positions they occupy when the circuit is brought from an inoperable to an operable condition; Fig. 7 shows these same parts, seen in Figs. 6 and 6^a, with others added; Fig. 8 shows these same parts, but when viewed as turned one fourth around; Fig. 9 shows some of the parts seen in Figs. 4 and 5, but on a smaller

scale omitting many of the parts there shown for clearness of illustration; Fig. 10 shows, in a diagrammatic way, a modified construction of parts; Fig. 11 shows in front view portions of another embodiment of the invention disclosed in preceding figures; Fig. 12 shows in cross section two carriages and the two switch devices, the movable parts of which are actuated by an electromagnet, seen at the lower right hand corner of Fig. 11, and the retaining means with which the restoring means on the carriages coact to release the retaining means and restore the circuits to an inoperable condition; Fig. 13 shows the parts seen at the left of Fig. 12, but in the positions they occupy when the circuit or circuits are brought into an operable condition; Fig. 14 shows in front view portions of another embodiment of my invention, the circuits being shown in a diagrammatic way; I intend to claim this modification more specifically in my applications 234,357 and 234,358. Fig. 15 shows in cross section, but on an enlarged scale the portion of the apparatus seen at the upper left hand portion of Fig. 14; Fig. 16 shows the switch device seen in Fig. 15, but turned half way over and end for end; Fig. 17 shows the parts seen in Fig. 16 when looking from left to right of Fig. 16; Fig. 18 shows some of the parts seen at the right of Fig. 15, but with portions broken away and the parts in the position they occupy when the circuits controlled by bar or controller M' are brought into an inoperable condition; Figs. 19 and 20 show in front elevation details of the switch and controller actuating parts seen in preceding figures; Fig. 21 shows the parts seen in Fig. 16, but in the positions they occupy after the terminals of the switch and circuit have been closed and the controller has been moved by the segment of the eccentric gear there shown and the circuit is held closed by the retaining or holding means therein provided; Fig. 22 shows in cross section portions of another embodiment of this invention; Fig. 23 shows one of the switch devices and a portion of a carriage seen in Fig. 22; and Fig. 24 shows the same parts seen near the middle of Fig. 22, but with such parts in the positions they occupy when the circuit or circuits controlled thereby are in an operable condition.

In Figs. 1 to 9 inclusive there is shown one embodiment of my invention. As here

shown the signal circuits are rendered normally inoperable by bodily moving that portion of each circuit connected to the switch device into a position where it is inoperable by the means provided for operating such devices in giving the signals. As thus shown each switch device is provided with one portion, member or part which is bodily movable into and out of operable condition for giving signals, which member or portion has a part which is made yielding relatively to its point of attachment to the part by which it is carried and bodily moved, and, hence, the movement of such portion or member is not seriously interfered with when brought into engagement with the means it coacts with in closing the circuit or circuits. Also as thus shown there are two of these yielding parts for each of such portions or members thus mounted on a single support and they are insulated from each other and are adapted to operate two different signals, for instance, a signal in the car and a signal for one of the stations or floors of the building. Each of these movable members of the switch devices, when the devices and their respective circuits are brought into operable condition, contacts with a piece of conducting material mounted on a carriage which moves at a given or regulated rate of speed, as the elevator car or similar object moves, in front of and over such members at substantially right angles to the direction in which such members of the switch devices are mounted to move. The contact between such conducting material and movable members of the switch devices is a yielding one and it is also a rubbing or scraping contact. Each insulated part of the movable members or portions of the switch devices is connected to one pole of a source of energy and the conducting material, mounted to move with the carriage, is connected with the other pole. From this it results that when the movable members of the switch devices are moved into their normal positions there is an air space between the conducting material mounted on the carriage, and each of the movable members of the switch devices, as such material passes over them, sufficient to prevent the passage of current from one to the other and, hence, the switch devices and their respective circuits are in an inoperable condition. When the switch device or devices are moved toward the path of movement of the conducting material mounted on the carriage so that contact is made, between such member or members and the conducting material, current passes from one to the other and the signal or signals are operated and the switch devices and also the circuits connected therewith are in operable condition. That is, both the circuit and switch device are in condition to be operable by the pas-

sage of the conducting material over them, as the car or other object moves relatively thereto. Also as here shown automatic switches, operable by the movements of the mechanism by which the car or similar object is moved, or otherwise if desired, are employed to successively open and close portions of the circuit, so that as the car or similar moving object moves in one direction the circuit or circuits are broken for substantially one half of the signals and those for the other half are closed and the signals are operable by the signal operating switch devices shown, whenever the movable portions or parts thereof are moved, so as to put their circuits in operable condition for contact with the conducting material on the carriage, as it moves over the same. These automatic switches hold one portion of the circuit or circuits in the closed condition at substantially all times, for instance, as the car moves up the circuits for the "up" signals are closed at that switch and those for the "down" signals are open at that point or points, and vice versa, therefore, the desired circuits, accordingly as the car moves, are practically always closed by these automatic switches and, so far as such opening and closing of the circuits is concerned, they are normally in operable condition. Automatic switches of this general character or class are well known.

In Figs. 2 to 8 one construction and arrangement of parts is shown which are to have supplied, if desired, the circuits, signal devices and connections diagrammatically illustrated in Fig. 1 and operable as hereinafter described, and two (a plurality) cars are to be served, that is, signals are to be given to either of two cars. A, A², A⁴, &c., designate in these figures the switch devices connected with the signal circuits for giving signals to each of the "up" moving cars, there being, as here shown, two of such circuits connected with each switch device, one for the signal in the car and one for the signal at one of the stations or floors of the building. These signal circuits, (which include their respective switch devices,) are normally in an inoperable condition by reason of a portion of each circuit being normally out of the path of the movement of means which are provided for closing such circuits. As here shown a portion or portions of each of the switch devices are made movable relatively to such path of movement to bring the circuits into and out of operable condition. A¹, A³, A⁵, &c., designate the switch devices for giving the signals to each of the "down" moving cars. Each of these switch devices have two yielding parts for each of the movable portions or members, both of which are movable together, to put the circuits connected with them into operable or inoperable condition.

Each of these parts, as here shown, form a portion of their respective circuits. These parts for the "up" signals of moving cars are designated as a , a^2 , a^4 , &c., respectively, and for the "down" signals of moving cars, as a^1 , a^3 , a^5 , &c., respectively. Two of these parts or terminals, as a and a^2 , or a^1 and a^3 , are mounted on a single block of insulating material, and, therefore, each is insulated from the other. Thus the parts or terminals a and a^2 are mounted on insulating block m , terminals or members a^4 and a^6 on block m^2 , parts or terminals a^1 and a^3 on block m^4 and terminals or members a^5 and a^7 on block m^8 , &c. Each of these blocks of insulating material is in turn mounted on a movably mounted part or controller, as, n , n^1 , n^2 , &c., respectively, (as seen in Fig. 6,) which in turn is mounted to move in a fixed support, as o , o^1 , o^2 , &c., respectively. These fixed supports are mounted in the frame F of the apparatus. One of these supports, as o^1 of switch device A^1 , is seen in Fig. 6, and it is shown partly in section to better illustrate the relations of the parts. As here seen the block m^1 is seen when looking upwardly from the lower portion of Fig. 2, and portions of the means by which the controller or part n^1 and block m^1 are caused to move are shown. The block m^1 and movable controller or part n^1 are seen in Fig. 6 in their normal positions, that is, in the positions they occupy when the circuits and switch device are in an inoperable condition by reason of the circuit or circuits being broken at the parts or terminals a^4 and a^6 , which are then out of contact position relatively to the portion of the apparatus with which they contact to operate the signals. These terminals or members a^1 and a^3 , the insulating block m^1 and the part n^1 , to which such block is attached, are seen in the contact position in Fig. 4, and also in Fig. 6^a. These parts m^1 and n^1 are caused to move into the positions seen in Fig. 6 by a spring l^1 and to move into the positions seen in Fig. 6^a, in full lines, by an elbow lever q^1 engaging with a stud or projection p^1 on part or controller n^1 , a link, as r^1 , and armature s^1 , as seen in full lines at the right of Fig. 4. This armature s^1 is actuated by electromagnet S which is in circuit with a push button or circuit closing device at one of the floors of the building, so that when such button is pushed, by a person desiring to signal the car, a circuit is closed and the electromagnet is energized and the parts m^1 and n^1 are moved from the position seen in Fig. 6, against the stress of spring l^1 , into the position seen in full lines in Figs. 4, 9 and 6^a, where they are held by a retaining device T^1 , shown in Figs. 7 and 8, where the parts m^1 and n^1 are in their normal positions (as shown in Fig. 6), and the switch device and circuits are in an inoperable con-

dition. These yielding parts or terminals a , a^2 , a^4 , &c., blocks m , m^1 , m^2 , &c., controllers n , n^1 , n^2 , &c., springs l , l^1 , l^2 , &c., constitute movable members or portions of the switch devices, as A , A^1 , A^2 , &c. As 70 herein shown these movable members or portions of the switch devices are arranged quite near one another and it may be said that they are arranged at or near a common point. When these members, portions or 75 parts are thus arranged each one, when in operable condition, may be actuated independently of each of the others by a device or carriage of comparatively small size which is movable in a given path of movement as a 80 car or other similar object moves, as herein-after explained.

It will be entirely obvious to any mechanician that where more than one elbow lever, as q^1 , is connected with the link, as r^1 , 85 as seen in Figs. 2 and 5, that a single spring will move the parts, as n^1 , from the position seen in Fig. 6^a to that in Fig. 6. These retaining devices T , T^1 , T^2 , &c., are mounted to slide on studs or projections as u , u^1 , u^2 , 90 &c., more clearly seen in Fig. 7, formed on the fixed supports as o , o^1 , o^2 , &c., and they are moved into holding or retaining position by suitable springs as v , v^1 , v^2 , &c., one spring being sufficient for one device, as T^1 , 95 as indicated in Figs. 5 and 7. These retaining devices, as thus arranged, are always movable into retaining or holding position, whenever the part or parts, as n^1 , are moved against the stress of the spring or springs, 100 as l^1 , and room is made for the portion or portions as t^1 , t^1 , of device T^1 to pass under the lower end or ends of parts as n^1 , by the stress of spring or springs, as v^1 . Each of these retaining devices thus shown retain or 105 hold corresponding switch devices, as A^1 , A^1 , in operable condition, until such retaining device is moved from the position seen in Fig. 9 to that seen in Fig. 7. As thus shown each device, as T^1 , is provided with two projections, as i^1 , i^1 , by which the device is movable out of retaining or holding position and the controllers of the movable portions or members, as n^1 , may be released and the switch devices be restored to an inoperable 110 condition. These retaining or holding devices, as T , T^1 , T^2 , &c., are actuated into the retaining or holding positions by a spring or springs, as v , v^1 , v^2 , &c., and into releasing positions by means mounted on 115 the carriage B and carriage B¹. These carriages are, as shown, duplicates of each other, and they are mounted to move relatively to and past the switch and retaining devices, one carriage for each elevator car, 120 as X and X¹, as indicated in Fig. 1. These cars X and X¹ are caused to move by any well known or desired means suitable for that purpose. These means are indicated in Fig. 1 by ropes Y and Y¹ and wheels y and y¹, 125 130

respectively, and may be adapted to move as the car or cars move at any desired rate of speed. Connected with each of these car operating means there is a suitable speed reducing mechanism of any desired or known form, which may reduce the speed to the desired extent for moving the carriages B and B¹, one of which, as carriage B, is shown as being moved in one direction by the reducing mechanism R connected with car operating means y in any desired manner and cord, or rope x and the other carriage B¹ is shown as being moved by the speed reducing mechanism R¹ and rope or cord x¹. In practice it has been found that a reduction of speed by these reducing mechanisms of from twelve feet for the car to two or one and one half inches for the carriage, or thereabout, is a convenient extent of reduction in speed to make a compact apparatus for operating the signals for elevator cars, as the same are generally run at the present day.

The carriages B and B¹ are mounted to move and be guided by suitably shaped rollers, as b, b¹, b², &c., Figs. 2 and 3, mounted on suitable standards, as L, L¹, L², &c., attached to the frame F in any desired manner for this purpose, two of which standards may be made integral with one another or otherwise, as desired, as for instance, standards L³, L⁸, seen in Fig. 4, on which the grooved rollers b³ and b⁸ are mounted. These rollers, as b, b¹, b², &c., and standards, as L, L¹, L², &c., may be so arranged on the frame F that the carriages B and B¹ will at all times be held in position to operate as described, each carriage being preferably held within the grasp or under the control of at least two pairs of such rollers when at the two extremes of its movement by its reducing mechanism. Preferably the carriage or carriages, with the parts carried thereby, shall be of such a weight that gravity will suitably move it or them in one direction, the reducing mechanism controlling its speed of movement under the action of gravity, as well as when lifting such carriage against gravity. These carriages may be caused to move back and forth relatively to the switch and retaining devices in any desired manner, but the foregoing has been found a convenient manner in use. Attached to each carriage, but preferably insulated therefrom, are suitably shaped pieces of conducting material C and C¹, one for each carriage, with which one pole of the source of energy may be connected, if desired. These pieces of conducting material, as C and C¹, are preferably of such a shape that each moves past the switch devices with which it is to connect, and as shown, each one is formed of one piece of material having one portion suitably shaped to connect with the switch devices in operable condition to give signals when the car is moving

upwardly and another portion to connect with the switch devices in operable condition to give signals when the car is moving downwardly. Also as shown these pieces, as C and C¹, are so shaped that the switch devices, connecting with the signals for the floors of the building contact with such pieces before they do with the switch devices connecting with the signal in the car. The signals are preferably given as the car or cars approach the station or floor from which the signal was sent and also some little distance away. If desired the signal at each floor may be operated when the car is substantially three floors away while the signal in the car may be operated when the car is substantially two floors away. These pieces, as C and C¹, may be otherwise shaped as desired and they may be of any desired proportions to operate the signals and hold them operated for any desired distance, these being matters which each individual constructor will arrange to suit his needs. As thus shown the switch devices are each restorable to their inoperable condition at given points in the movement of each carriage relatively to the floors of the building, and when thus restored the signals are extinguished or cease to act as such, until the switch device or devices are again brought into operable condition by the means employed for this purpose. The point or points at which these switch devices and circuits are to be restored to an inoperable condition or cease to operate is also a matter which will be determined by each individual constructor.

Each carriage, as shown, has attached to it, two pivotally mounted parts, as c and c¹ for carriage B, or c² and c³ for carriage B¹, which coöperate with projections, as i, i¹, i², &c., on retaining devices T, T¹, T², &c., to move such retaining or holding devices out of engagement with the movable parts of the switch devices, as n, n¹, n², &c., to release such parts and restore the switch devices and their circuits to an inoperable condition.

The pivoted pieces, as c, c¹, c², c³, &c., form restoring means which, as shown, act on the projections, as i, i¹, i², &c., on retaining devices, as T, T¹, T², &c., to move such devices out of retaining or holding positions and release the movable portions or members of the switch devices and restore the same and their circuits to an inoperable condition. Pivoted pieces, as c and c², act on one portion of these retaining devices, as the carriages, as B and B¹, respectively, move in one direction and pieces, as c¹ and c³, act on another portion of these retaining devices as such carriages move in the other direction. These pieces, as c, c¹, c² and c³, are preferably pivoted to brackets, as c⁴, c⁵, c⁶ and c⁷, Fig. 4, and are substantially free to move in one direction, but are held in actuating position

and against movement in the other direction by pins or projections, as c^8 , c^9 , c^{10} and c^{11} , as indicated in Fig. 5. Springs, such as c^{14} in the lower half of Fig. 5, tend to normally hold these pivoted pieces in contact with their respective pins or projections, but permit such pieces to yield and move out of actuating position or away from their respective pins, when force is applied in a direction to thus move them. From this it follows that if the pivoted piece, as c^2 , seen in Fig. 5, moves in the direction of the arrow adjacent thereto the pin or projection as c^{10} , will prevent such piece as c^2 , from being moved and it will be held in actuating position, so that the inclined face at its end will engage with the projection, as i^1 , on retaining device, as T^1 , and actuate the same, moving it against the stress of its actuating spring, as v^1 , until the movable parts or controllers, as n^1 , of switch devices, as A^1 and A^1 , have been released from the retaining or holding action of the projecting parts, as t^2 and t^3 , and permitting the stress of the spring or springs as l^1 and l^1 , on controllers, as n^1 , n^1 , of switch devices, as A^1 and A^1 , to move such movable portions or members and restore the switch devices to an inoperable condition. If the retaining device, as T^1 , seen in Fig. 5 is in the position there seen and the carriage is moving so that pivoted piece, as c^2 , moves in a direction opposite to that indicated by the arrow, then, assuming that the piece had been moved by the carriage below projection, as i^1 , as it would have done in actuating the retaining device, as T^1 , in ordinary practice, that edge of this piece, as c^2 , which rests against pin or projection, as c^{10} , would engage with projection, as i^1 , and, as the carriage moved upwardly, such piece c^2 would be moved out of actuating position against the stress of spring, as c^{14} , until piece, as c^2 , could pass projection, as i^1 , without moving it or the retaining device, as T^1 . Then as the carriage moved on the spring, as c^{14} , would restore this pivoted piece c^2 into its actuating position, that is, to the position there seen, ready to actuate device T^1 as the carriage moves in the return direction, or in the direction indicated by the arrow, as just before explained. These pivoted pieces are thus active as the carriage moves in one direction upon one portion of the retaining devices and inactive upon another portion no matter in which direction the carriage moves, relatively to the switch and retaining devices. These pivoted pieces also form means which are active to move some one or more of the retaining devices as the carriage moves in one direction and also are inactive to move the same retaining devices when the carriage moves in the other direction. They also form portions of restoring means which are adapted to move relatively to the retain-

ing devices in two directions and provide means which are active on some and inactive on other of the retaining devices when moving in one direction and active on the devices when moving in the other direction, 70 on which such means was before inactive. They also form means for restoring the switch devices and circuits to an inoperable condition portions of which are separately mounted to move relatively to the retaining devices, that is, one portion as c and c^1 , is mounted on carriage B and another portion, as c^2 and c^3 , is mounted on carriage B^1 , and, hence, each portion is mounted to move as its own individual carriage moves independently of the movement of any other carriage, the movement of one carriage not affecting the movement of the other, as each moves in accordance with the movement of the car with which it is connected. These pivoted 80 pieces, by reason of being mounted on the carriages, necessarily move in unison therewith, and, as the conducting pieces, as C and C^1 , are also mounted on the carriages, such pivoted pieces also move in unison with the 85 conducting pieces as they move relatively to the switch and retaining devices.

Each elevator car or similar object is provided with an automatic switch, as shown in Fig. 1, which is operable as the car 95 changes its direction of movement. These automatic switches, as E, E^1 , are each provided with four contact points and a pivoted arm, so combined with the car operating means that as the car moves in one direction this arm is in electrical connection with two of the four contact points and when the car reverses its direction of movement such arm moves, breaking electrical connection with such two contact points and 100 making electrical connection with the other contact points, this taking place with each reversal of the direction of movement of the car and carriage. These switches as E and E^1 , are preferably arranged in connection 105 with some revolving part of the car operating means, so that some portion of the switch, as J, or J^1 , is in frictional contact with such revolving part of the operating means and it has a limited extent of movement as such revolving part reverses its direction of movement, which extent is sufficient to move the pivoted arm, as e, of switch, as E, or of arm, as e^1 , of switch, as E^1 , the distance required to connect and disconnect such arms with and from the pairs 110 of contact points, as shown in Fig. 1. Switch, as E, is provided with contact points, as e^2 , e^3 , e^4 and e^5 , and switch, as E^1 , with contact points, as e^6 , e^7 , e^8 and e^9 , and 115 the switch arms, as e and e^1 , are seen in the position they occupy, as car X moves upwardly and car X^1 moves downwardly.

The source of energy, as D, as seen in Fig. 1, has a wire 1 leading therefrom and con- 120

necting with switch arms, as e and e^1 . This wire 1 connects also with wires 2 and 3 which lead to and through signal devices, as G, G^1 respectively, and back as shown, so that wire 2 connects with contact points e^3 and e^4 of automatic switch, as E, by branch wires h and h^1 , and wire 3 connects with contact points, as e^5 and e^6 , of switch, as E^1 , by branches h^2 and h^3 . Only one of the contact points, as e^3 and e^4 , is in electrical connection with switch arm e at a time, point e^4 is in contact when car X is moving up and point e^3 when such car is moving down. Also only one of the contact points, as e^5 and e^6 , is likewise in contact with the arm, as e^1 , contact point, as e^7 , being in contact, as car X^1 moves down and point, as e^8 , being in contact as such car moves up. When contact point, as e^4 , is in electrical connection with switch arm, as e of automatic switch, as E, the circuit is through wires 1, 2, h^1 to wire 4 which leads to the yielding parts of movable portions or members, as a^2 , a^6 , a^{10} , &c. of the switch devices, as A, A^2 , A^4 , &c., which, when such devices and their circuits are in operable condition, contact with conducting material, as C, as it moves over them. Whenever this piece, as C, is in contact with any one of the yielding parts of movable members or portions, as a^2 , a^6 , a^{10} , &c., the circuit is continued by wire 5 to the other pole of the source, as D, as shown in Fig. 1. When car X reverses its direction of movement automatic switch arm e moves and breaks connection with points, as e^4 and e^5 , and connects with points, as e^2 and e^3 , and then the circuit is from wire 2 to branch wire h contact point e^3 , thence by wire 8 to movable parts, as a^1 , a^5 , a^9 , &c., of switch devices, as A^1 , A^3 , A^5 , &c., for car X, thence to conducting material C, and thence by wire 5 to the other pole of the source D. Thus when car X moves upwardly, as shown in Fig. 1, the signal device G is in circuit by reason of wire 1 being in electrical connection with arm e of switch E by means of branch wire h^1 and point e^4 , and such connection is broken through point e^3 and wire h . When the car reverses its movement the connection between point e^4 and arm e is broken and connection is made through contact point e^3 and such arm thereby changing the flow of the current as just described. For car X^1 and its carriage C ^{1} , as shown in Fig. 1, with car moving down, the circuit is by wire 1 to wire 3 thence to and through signal G ^{1} back to wire h^2 to contact point e^7 , of switch E^1 , to arm e^1 , thence by wire 6 to movable yielding parts, as a^1 , a^5 , a^9 , &c., of switch devices, as A^1 , A^3 , A^5 , &c., for car X^1 , thence to conducting material C ^{1} of carriage B ^{1} and by wire 7 to wire 5 and the other pole of source D. When car X changes its direction of movement a change of the switch

arm e^1 takes place and the connection between it and contact points, as e^6 and e^7 , is broken and connection is made between such arm and contact points, as e^8 and e^9 , so that as such car moves upwardly the circuit is by wire 1 to wire 3, thence through signal device G ^{1} and back to branch wire h^3 , contact point e^8 , arm e^1 and thence by wire 9 to movable yielding parts, as a^2 , a^6 , a^{10} , &c., of switch devices, as A, A^2 , A^4 , &c., and thence to conducting material C ^{1} and to wires 7 and 5 to the other pole of the source D. The operation for this car X ^{1} is the same as for car X and as many cars and carriages with conducting material may be added as desired, as each car may be provided with the same or duplicate circuits of those shown for either of cars X or X ^{1} seen in Fig. 1. Of course it will be understood that each switch device and circuit which is in an inoperable condition by reason of the movable member or members thereof being in the position or positions seen in Figs. 7 and 8, as before described, there will be an air space between such member or members and the pieces of conducting material C and C ^{1} , as the latter move over such members, but that with each of the movable members or portions of the several switch devices moved into the position indicated in Figs. 6 ^{a} and 9, the circuits will be as described above during the movement of the cars and carriages for the full extent of movement for the several floors which are designed to be served by the particular system or apparatus.

It will be observed that whenever the car and its respective carriage change their direction of movement the automatic switches break and make connections, as described above. Also that any movable member or members that are in position for the pieces of conducting material to electrically connect with the yielding part or parts thereof in passing over the same and which are connected with contact points which at the time are out of contact with the switch arms, are incapable of operating the signal devices, and, hence, the signals will be operated only as the car moves in proper direction for the signals to be given.

The circuits for the floor signals of car X, when moving up, as shown in Fig. 1, are as follows: from source D by wire 1 to switch arm e , contact point e^5 , thence by wire 10 through signal device H ^{14} , and by wire 11 to movable yielding part, as a^{28} , of switch device, as A ^{14} , of that car and thence by piece of conducting material C and wire 5 to the other pole of source D. It will be observed that wire 10 connects with each of the signal devices H, H ^{2} , H ^{4} , &c., at the several floors, which are operable, as car X moves upwardly, and ends with the lowermost signal device H ^{14} . The circuit for the next signal is by wire 10 through signal device H ^{12} .

and by wire 12 to part a^{24} of switch device A^{12} , thence to conducting material C and by wire 5 to the other pole of the source. It is to be understood that conducting piece of material C is at all times in electrical connection with source D by wire 5, so that any circuit reaching piece C is in connection with that pole of such source. This is also true of conducting piece of material C^1 and wires 7 and 5, as seen in Fig. 1, and consequently, in tracing the circuits for signal devices H , H^1 , H^2 , H^3 , &c., it will not be necessary to trace them further than to pieces C and C^1 . The circuit for the next signal is by wire 10 through signal device H^{10} and by wire 13 to part a^{20} of switch device A^{10} and piece C. The next one is by wire 10 through signal device H^8 , by wire 14 to part a^{16} of device A^8 and piece C. The remaining circuits for signal devices H^6 , H^5 , H^2 and H are by wire 10 and wires 15, 16, 17 and 18, respectively, through said signal devices to yielding parts a^{12} , a^8 , a^4 and a , respectively, and thence to piece C. The circuits for the floor signals as car X moves downwardly are as follows: from switch arm e , contact point e^2 to wire 19, leading to all of the signal devices H^1 , H^3 , H^5 , &c., as in the case of wire 10 and devices H , H^2 , H^4 , &c., and thence to the respective signal devices H^1 , H^3 , H^5 , H^7 , H^9 , H^{11} , H^{13} and H^{15} , and by wires 20, 21, 22, 23, 24, 25, 26 and 27 respectively to parts a^3 , a^7 , a^{11} , a^{15} , a^{19} , a^{23} , a^{27} and a^{31} , respectively, and to conducting material C and source D.

The circuits for the floor signals of car X^1 are substantially, as seen in Fig. 1, duplicates of those for car X and the same can be readily traced without describing them in detail. Wires 30 and 31 are substituted in the circuits for car X^1 for wires 10 and 19 in the circuits for car X. Also wires 32, 33, 34, 35, 36, 37, 38 and 39 are substituted in the case of car X^1 for wires 11, 12, 13, 14, 15, 16, 17 and 18, respectively, of car X, and wires 40, 41, 42, 43, 44, 45, 46, and 47 are also substituted in the case of car X^1 for wires 20, 21, 22, 23, 24, 25, 26 and 27, respectively, of car X, all as shown. The movable members and parts of the switch devices A , A^1 , A^2 , A^3 , &c., are moved into position to put the switch devices and circuits in operable condition from their normal or inoperative condition by ordinary push-buttons or other circuit closing devices located at the respective floors of the building, there being one for each of the switch devices for up-going signals and one for down going signals at each floor, as indicated diagrammatically in Fig. 5, wherein push-button N is for an upgoing signal and push-button N^1 is for a downgoing signal. Electromagnet S^4 in Fig. 5 is connected with push button N and source D^1 by wires 48, 49 and 50. Push button N^1 and source D^1 are connected

by wires 51, 52 and branch wire j^1 , so that magnet S^1 can be energized upon operating push button N. From this it will be seen that the push button portion of the means for bringing each circuit into operable condition is arranged at or near the station or floor in convenient position to be operated as desired and that another portion of such means is arranged adjacent to the movable portion or part of the circuit which is to be moved to bring such circuit into operable condition.

If desired the retaining or holding devices may be constructed and made to operate somewhat differently from what they are shown in preceding figures, for instance, as seen in a diagrammatic way in Fig. 10, where there are no movable members or parts of the switch devices such as are shown in preceding figures. In this Fig. 10 springs, similar to those shown in preceding figures as forming one terminal of a circuit, are mounted on fixed supports and they form terminals of circuits as before, but they are not mounted to move into and out of position to put the switch devices and circuits in an inoperable or operable condition. This is done by a separate switch device, as K, having an elbow lever k one arm of which is provided with an armature k^1 , which electromagnet O operates, when energized by push buttons N^2 being operated and the circuit through source D^2 closed. The other arm of this elbow lever k is provided with conducting material k^2 with which one pole of source of energy D^3 is connected by wire 53. Conducting material k^2 , when magnet O is energized, connects with spring arm k^3 and makes electrical connection therewith. This spring arm k^3 is electrically connected with car signals G^2 and G^3 , one for one car and the other for another car, by wire 54, and signal device G^2 is connected with contact spring a^{32} of switch A^{16} by wire 55 and device G^3 is connected with contact spring a^{34} , of switch A^{17} , by wire 56. Contact spring a^{32} is in electrical contact with conducting material C^2 , when the carriage, on which material C^2 is mounted, moves over such spring and switch K is closed, and contact spring a^{34} is in electrical contact with conducting material C^3 , when the carriage, on which such material is mounted, moves over this spring a^{34} , and switch K is closed. Conducting material C^2 is connected with switch E^2 by wire 57 and material C^3 is connected to switch E^3 by wire 58. Switches E^2 and E^3 are connected with the other pole of source D^3 by wire 59. Spring arm k^3 is also connected by wire 60 with signal devices H^{16} and H^{17} for one floor of a building, as either up or down signals for two cars, accordingly as one chooses to consider them. Signal device H^{16} is connected to contact 130

spring a^{33} , of switch A^{16} , by wire 61 and device H^{17} is connected with contact spring a^{35} , of switch A^{17} , by wire 62. These contact springs, as a^{33} and a^{35} , like springs a^{32} and a^{34} are in electrical contact with pieces, as C^2 and C^3 , respectively, when such pieces are passing over them and switch K is closed.

As here shown there are two parts for two cars, when such cars move in one direction, as for instance, when moving in either the "up" or "down" direction. As thus shown, if signals are to be given when the cars are moving in both the "up" and "down" directions, then the floor signal devices, as G^2 G^3 , contact springs, as a^{32} , a^{33} , a^{34} , a^{35} and switches E^2 , E^3 , K , would have to be duplicated in order that separate signals be given at each floor or station in both the "up" and "down" directions as it takes one set of these devices working independently of all others for giving signals in the "up" direction at each floor and another similar set for giving the signals in the "down" direction. In addition, the conducting material, as C^2 and C^3 , would have to be extended or widened to accommodate the duplicate sets of contact springs with which such conducting pieces contact to give the signals. The switches as E^2 , E^3 , would have to be duplicated in order that the circuits would be alternately opened and closed accordingly as the car moves in the "up" or "down" directions, as explained in connection with the embodiment of my invention shown in preceding figures of the drawings. This duplication of the above mentioned parts would, of course, require that proper connections by wires, etc., be made with such parts and the source of energy so that the signals would be operated as they are described to be operated when arranged as heretofore shown, where signals are to be given in both the up and down directions. This necessarily requires that the duplicated parts are to be so connected that when the car moves in the "up" direction the "down" signals will not be operated and also that when such car moves in the "down" direction the "up" signals will not be operated. As heretofore explained in connection with preceding figures, the circuits for giving the signals when the car is moving in the "up" direction, are closed by the movement of a part of a switch, as E or E^1 and the circuits for the giving of signals as the car moves in the "down" direction are opened by the movement of a similar part of the same switch. In order that the circuits for giving signals at the different floors or stations in both directions of movement of the car in the modification shown diagrammatically in Fig. 10, the switches, as E^2 and E^3 , must be duplicated and made operable to do the

work done by the switches, as E and E^1 in the embodiment disclosed in preceding portions of this specification. These switches E^2 , E^3 referred to, shown diagrammatically have a function similar to the switches E E^1 shown in Fig. 1. The contact springs are at all times in position, in the construction seen in Fig. 10, for pieces of conducting material C^2 and C^3 to contact therewith, as such pieces move over them, but the circuits with source D^3 are broken at switch K , when that switch is open, and, therefore, the signals can only be operated when that switch is closed. This switch is closed by magnet O , source D^2 and push button N^2 , as before explained, wire 63 leading from magnet O to source D^2 , wire 64 leading from said source to push button N^2 and wire 65 leading from such push button to magnet O , as shown. As switch device K is closed a projection, as k^4 , engages with the upper end of the lever t^{16} , which lever forms a portion of the retaining device T^{16} . When lever t^{16} and projection k^4 are thus engaged the switch K is held or retained in the closed condition and when either piece C^2 or C^3 pass over their respective contact springs the respective signals will be operated until such switch is released and the circuit or circuits is restored to an inoperable condition. This switch K is released by means of bars, as I and I^1 , having projections, as i^{16} and i^{17} , respectively, with which restoring devices, as f and f^1 , suitably mounted on conducting pieces, as C^2 and C^3 , respectively, engage to move such bars. Restoring device, as f , mounted on piece, as C^2 , as indicated in Fig. 10, has not reached or has passed by projection i^{16} on bar I , according to the direction of its travel, and, hence, bar, as I , is in its normal position ready to be forced toward retaining device T^{16} , so as to force lever t^{16} into the position seen. Bar I^1 is shown as having been forced toward lever, as t^{16} , by restoring device, as f^1 , carried by piece, as C^3 , contacting with projection, as i^{17} . When restoring device, as f^1 , has passed by projection, as i^{17} , bar I^1 is free to be moved toward piece C^3 . If desired additional springs k^6 and k^7 , one for each bar I and bar I^1 may be employed as indicated in Fig. 10. This lever t^{16} is operable by either bar I or bar I^1 accordingly as restoring devices f or f^1 engage with projections i^{16} or i^{17} of such bars and when once operated it remains in the position seen until magnet O is again energized and switch K is closed, no matter how many times restoring devices f and f^1 may actuate bars I and I^1 .

Elbow lever k is caused to move out of contact with spring arm k^3 by any suitable means, as for instance a spring or springs. As shown there are two springs, k^8 and k^9 , preferably arranged so as to act somewhat

differently. As shown spring h^8 is of comparatively light tension and exerts its stress throughout the movement of arm h and spring h^9 is of comparatively strong tension and exerts its force through only a portion of the movement of arm h , and that portion when armature h^1 is nearest electromagnet O . With this arrangement of springs the arm h may be made to move out of contact with spring arm h^3 with a quick movement and the magnet O can move its armature from a greater distance than if a single spring of sufficient stress to give this quick movement was used, as is well known. This gives a quick break of the current, as the arm h moves out of contact with spring arm h^3 , which is very desirable with a current such as is suitable for electric light purposes.

In Figs. 11, 12 and 13 a different form of restoring device is illustrated from what is shown in Figs. 1 to 9, and the retaining devices are made to engage with the blocks of insulating material on which are the contact springs or yielding parts with which the conducting pieces mounted on the carriages contact as they pass over such springs or parts. These blocks, m^{18} , m^{19} , m^{20} , &c., of insulating material are mounted on movable parts or controllers n^{18} , n^{19} , n^{20} , &c., which are actuated in one direction by springs l^{18} , l^{19} , l^{20} , &c., as the corresponding parts are operated in the construction seen in Figs. 1 to 9. These parts are also operated in the other direction by elbow levers, q^{18} , q^{19} , q^{20} , &c., links r^{18} , r^{19} , r^{20} , &c., to which armatures s^{18} , s^{19} , s^{20} , &c., are attached and electromagnets, S^{18} , S^{19} , S^{20} , &c., which are connected with push buttons located at the several floors by circuits and which are operable as before explained, to bring the movable portions or members having yielding parts or contact springs a^{36} , a^{37} , a^{38} , &c., into position to make contact with suitable pieces of conducting material C^4 and C^5 mounted on carriages B^4 and B^5 and put the switch devices and their respective circuits in an operable condition, the same as in the construction shown in Figs. 1 to 9, and as before explained. Two of these movable members or portions having parts a^{36} , a^{37} , a^{38} , &c., are mounted on each of these blocks of insulating material m^{18} , m^{19} , m^{20} , &c., as in Figs. 1 to 9, and with the other parts form switch devices A^{18} , A^{19} , A^{20} , &c., which are normally in an inoperable condition, that is, in a condition where there is a clear space between the pieces of conducting material C^4 and C^5 , as such pieces pass over the yielding parts or contact springs, of the movable members or portions, a^{36} , a^{37} , a^{38} , &c., of the switch devices, and no current can flow from one to the other. As shown in these Figs. 11 to 13, the restoring devices consist of pivoted plates c^{20} , c^{21} , c^{22} and c^{23} mounted upon the carriages B^4 and B^5 ,

respectively, two plates for each carriage, as shown. The outermost edges of these plates which are arranged to extend beyond the edges of the carriages, as plates c^{20} and c^{23} are seen act upon the projections, as i^{26} and i^{27} to force such projections and retaining devices away from their respective carriages and out of engagement with their respective blocks of insulating material to release the movable members or portions of the switch devices and restore such devices and their circuits to an inoperable condition by the action of springs l^{26} and into the position seen in Fig. 12, where the parts are shown with plate or restoring device c^{20} in the position relatively to projection i^{26} of retaining device or devices T^{26} as shown in Fig. 11 and where the carriage B^4 is moving upwardly, as indicated by an arrow. Restoring device c^{20} is there shown as having performed its work on retaining device T^{26} and in position to perform its work upon any other retaining device with which it is to engage on the movement upwardly of the car and carriage B^4 , until such car and carriage reverse their direction of movement. Whenever this occurs these pivoted plates or restoring devices will also reverse or change positions, one with the other, so far as concerns the portions of them which extend beyond the outer side edges of the carriages; that is, device c^{20} will move inwardly into the position, relatively to the side edge of the carriage, corresponding to that device c^{21} is now seen to occupy and device c^{21} will move outwardly into a position, corresponding to that device c^{20} is now seen to occupy, all as is illustrated in the case of devices c^{22} and c^{23} and carriage B^5 , which is shown as moving downwardly or in a direction opposite to that in which carriage B^4 is shown as moving, as indicated by the arrows thereon.

When carriage B^4 is moving up device c^{21} is out of active relation to projections, as i^{27} , on retaining devices, as T^{27} , and device c^{20} is in active relation to projections, as i^{26} , on retaining devices, as T^{26} , while in the case of carriage B^5 device c^{23} is in active relation to projections, as i^{27} and device c^{22} is out of active relation to projections, as i^{26} . As these carriages reverse or change their direction of movement these restoring devices change relations to their respective projections with which they co-act in the operation of the apparatus. This change in the relations of the restoring devices and their respective projections is accomplished by means of pivoted levers, as Q and Q^1 , one on each carriage. Each lever, at one end, is provided with a friction plate or device, as Q^2 and Q^3 , respectively, and at the opposite ends with pins or projections, as Q^4 and Q^5 , which work in slots Q^6 and Q^7 , respectively, of restoring devices, as c^{20} , c^{21} , 130

c^{22} and c^{23} , as shown. These slots, as Q^6 and Q^7 , are of suitable shape and dimensions to accomplish the change in the relations of such devices relatively to the carriages 5 and their respective retaining device projections, as just explained, when the carriages change their direction of movement. The friction devices, as Q^2 and Q^3 , bear upon friction bars, as Q^8 and Q^9 , respectively, and there is sufficient frictional contact between them, so that the levers will be moved to the extent desired before device, as Q^2 or Q^3 , will slide on bar, as Q^8 or bar Q^9 , respectively, suitable means being employed to secure such bars in fixed 15 positions on frame F^1 and also to limit the extent of movement of these levers, as Q and Q^1 . As shown the ends of the slots as Q^6 and Q^7 , in devices, as c^{20} , c^{21} , c^{22} and c^{23} , respectively, do this work of limiting the 20 extent of the movement of such levers. If desired other constructions and arrangements of retaining or holding devices may be employed to hold differently formed 25 movable members or parts of switch devices in operable condition so that a carriage or carriages may coöperate therewith and release such members and parts and restore the switch devices and their circuits to an 30 inoperable condition, such for instance as is shown in Figs. 14, 15, 16 and 17 of the drawings. In the construction shown in these figures the retaining devices are actuated in one direction by springs and in the 35 other by restoring devices mounted on a carriage or carriages, and in this respect these devices are essentially the same as the retaining and restoring devices in preceding figures. Also in this construction 40 there are movable members or portions of the switch devices which are movable into and out of position where they can be operated by some part or portion mounted on a carriage or movable means engaging there- 45 with and the circuits and switch devices are in an operable or inoperable condition, accordingly as such movable members or portions are in or out of position to be operable by the carriage or carriages in passing over 50 or relatively to them, and in this respect the construction here shown is like that shown in some of the preceding figures of the drawings. Also these movable portions or members are provided with a part or 55 parts which yield and permit such portions or members to move into the operable position as in the construction seen in Figs. 1 to 12. Also in this construction the restoring devices are active or inactive to release the movable members or portions of the switch devices accordingly as the retaining or holding devices are or are not holding or retaining such members or portions in position for their circuits to be in 60 an operable condition as the carriage or car-

riages move relatively thereto, and in this respect also, this construction is substantially like that shown in preceding figures.

Instead of the switch devices being mounted to move in separate supports, as in some of the preceding figures they are, in the construction shown in Figs. 14 to 17 mounted on a bar or controller, which in turn is mounted in bearings to move back and forth to the desired extent; that is, the corresponding switch devices for a plurality of cars are thus mounted instead of each of such corresponding devices being mounted to move in its own separate support. In this respect the construction shown in Figs. 14 to 17 is different from any shown in preceding figures. Two of these bars or controllers are shown and these somewhat widely separated, but it is to be understood that two of such bars or controllers may be used for each floor to be served with signals, one for "up" signals and one for "down" signals. One of these two controllers shown is for "down" signals and one is for "up" signals, and a description of these two will suffice for any number, as they will be substantially the same in mode of operation. These bars or controllers M and M^1 , one, M , being for the switch devices giving signals for one floor, when the cars are moving downwardly, and the other, M^1 , being for switch devices giving signals for one floor, when the same cars are moving upwardly, are mounted to slide in bars, P , P^1 , fixedly attached to the frame F^2 . These controllers are actuated or moved in one direction and into the position occupied by controller M^1 ready for the circuits to be closed, by springs, as P^2 , P^3 , respectively, and these springs normally tend to thus move these controllers from the position controller M occupies to that occupied by controller M^1 . These controllers are moved in the opposite direction by the segments of eccentric gears n^{28} , n^{29} , n^{30} and n^{31} engaging with racks C^6 , C^7 , C^8 and C^9 on carriages B^6 and B^7 , when in position for this to be done and the carriage or carriages are moving in the proper direction. It will be observed that controller M has been moved by the downward movement of rack C^8 and its engagement with segment n^{29} into the position seen in Fig. 14, and also that rack C^8 has passed on beyond segment n^{29} leaving the movable part o^{29} held in position to hold the movable members or portions with the springs a^{56} and a^{57} in contact and the circuit closed between them and with the signal device connected therewith in operation. These several movable members or portions and contact springs a^{54} , a^{55} , a^{56} , a^{57} , &c., are mounted on blocks m^{30} , m^{31} , m^{32} and m^{33} , respectively, of insulating material, two springs to each block. Each of these contact springs forms one terminal of a circuit, which circuit is closed

when the springs are in contact, and is open when such springs are out of contact one with another. These blocks m^{30} , m^{31} , m^{32} and m^{33} and the contact springs mounted thereon form portions of switch devices A^{30} , A^{31} , A^{32} and A^{33} , which are mounted on these controllers M and M^1 , blocks m^{30} and m^{31} being mounted on controller M and blocks m^{32} and m^{33} being mounted on controller M^1 . Switch device A^{30} coöperates with rack C^6 , of carriage B^6 , device A^{31} with rack C^8 of carriage B^7 , device A^{32} with rack C^7 of carriage B^6 and device A^{33} with rack C^9 of carriage B^7 , in giving the signals or causing the signal devices to operate. As these controllers M and M^1 are moved from the position controller M^1 occupies to that occupied by controller M , by the eccentric segments n^{28} , n^{29} , n^{30} and n^{31} , engaging with their respective racks, spring pressed stops, as M^2 and M^3 attached to armatures M^4 and M^5 , respectively, engage with fixed stops M^6 and M^7 , respectively, and hold such controllers from immediately returning to the positions from which they were thus moved and they are held until the spring pressed stops M^2 and M^3 are operated by energizing electromagnets O^1 and O^2 , respectively, and springs P^2 and P^3 are allowed to move such controllers and return them into position where their respective switch devices and their circuits will be in operable condition until such controllers are again moved by the segmental eccentrics and the retaining devices have been operated and the movable parts of the switch devices are released and such devices and circuits are restored to an inoperable condition. In this construction the blocks m^{30} , m^{31} , m^{32} , m^{33} , the springs a^{54} , a^{55} , a^{56} , a^{57} , &c., and the controllers M and M^1 constitute movable portions or members of the switch devices.

Each armature is provided with a spring as Q^x , Fig. 15, which has to be compressed when magnet O^2 is energized, to release stop stop M^3 from stop M^7 fixed to bar M^1 . This spring normally tends to press stop M^3 into position for it to thus engage, as shown in Fig. 18. As shown in Fig. 15 controller M^1 is in the same position shown in the upper part of Fig. 14, that is, with the stop M^3 released from stop M^7 and with the controller moved by the stress of its spring P^3 into position for either segment n^{31} or segment n^{30} to engage with their respective racks on the upward movement of such racks, and whichever rack reaches its respective segment first will operate the same and move controller M^1 from the position in which it is shown in Fig. 15 to that seen in Fig. 18, which corresponds with the position of controller M seen in the lower part of Fig. 14. As seen in Fig. 14 the controller M is in the retained position where the racks cannot contact with the segmental eccentrics and

no action on the switch devices can be had until such controller and eccentrics are in the positions seen in Fig. 15, or the upper part of Fig. 14. These segmental eccentrics are mounted on studs o^{28} , o^{29} , o^{30} and o^{31} , respectively, and these studs are in turn mounted or fixed in the controllers, studs o^{28} and o^{29} being fixed in controller M and studs o^{30} and o^{31} being fixed in controller M^1 . On each of these studs there is also pivotally mounted a movable part, as s^{28} , s^{29} , s^{30} and s^{31} , respectively, with which eccentrics n^{28} , n^{29} , n^{30} and n^{31} , coöperate. One of these eccentrics, as n^{31} , is seen detached from its stud in Fig. 19 and one of these movable parts, as s^{31} is seen detached from the stud in Fig. 20. As here seen the eccentric is provided with a stud or projection p^{31} with which the small end of movable part s^{31} engages as such eccentric moves in a direction to move the controller; as above explained, and the two move as one part would move, and consequently eccentric n^{31} and movable part s^{31} move together and the latter is operated by the former as it is actuated by its rack coöperating therewith, but the eccentric is free to move in the other direction whenever released from the control of the rack on the carriage. This eccentric n^{31} is provided with a second pin or projection p^{40} with which a two armed spring l^{31} engages, one arm with one side of the pin and the other with the other side. As a result eccentric n^{31} is free to move in either of two directions against the stress of this spring, which is seen in Figs. 16 and 17. There is a pin p^{50} , Figs. 16 and 17, attached to controller M^1 with which the two arms of spring l^{31} engages to keep such arms under tension and limiting the movements of such arms in a well known manner. Movable part s^{31} is provided with a pin or projection r^{31} , preferably insulated therefrom by being in insulating material or otherwise, which, as such part is moved by eccentric n^{31} , engages with contact spring a^{61} and moves it down into contact with contact spring a^{66} , closing the circuit and operating the signal until the two springs are moved out of contact. Corresponding springs a^{56} and a^{57} are seen in contact in switch device A^{31} , as before explained. When eccentric n^{31} has moved part s^{31} and closed spring a^{61} down against spring a^{60} these springs yield and permit pin or projection r^{31} to continue its movement, the contact surfaces of the springs rubbing on one another until the eccentric n^{31} has done its work of moving controller M^1 into position seen in Fig. 18. In this movement of the eccentric n^{31} , the part s^{31} will be moved so that the outermost upper edge of such part, as seen in Fig. 16, will be in the position seen in Fig. 21, permitting portion t^{31} of the retaining device T^{31} , to pass beyond and

over such edge, by the action of spring v^{31} , into the position seen in such Fig. 21. In this movement of segment n^{31} it turns on its stud o^{31} until it has turned far enough for its last tooth to pass over the teeth of the rack, when such turning movement ceases and the segment is practically disengaged from its rack. When eccentric n^{31} passes out of engagement with its coöperating rack 10 movable part s^{31} will move backwardly, by the action of contact springs a^{61} and a^{60} , as far as portion t^{31} of retaining device T^{31} will permit and the retaining device will hold or retain such movable part s^{31} , pin r^{31} 15 and contact springs a^{61} and a^{60} in the positions seen in Fig. 21, until such retaining device is moved against the stress of its spring v^{31} and out of engagement with part s^{31} , when such part, by the action of the contact springs, will be moved into the position 20 seen in Fig. 16 and the circuit will be broken quickly, as there is practically little if any resistance to the movement of part s^{31} on its stud o^{31} , either before or after spring a^{61} 25 has moved out of contact with spring a^{60} . When the eccentric n^{31} fully disengages from its rack, spring t^{31} acts and returns it to its normal position, as seen in both Figs. 16 and 21, hence, contact spring a^{61} , aided 30 somewhat by spring a^{60} , does not have to move such eccentric, and only moves movable part's s^{31} , as explained.

Retaining devices T^{28} , T^{29} , T^{30} and T^{31} are mounted to slide back and forth to a limited 35 extent in suitable supports u^{28} , u^{29} , u^{30} and u^{31} fixed to the controllers M and M^1 . These retaining devices are actuated in one direction by their springs v^{28} , v^{29} , v^{30} and v^{31} , respectively, and they are actuated in the other 40 direction by inclined surfaces c^{26} , c^{27} , c^{28} , and c^{29} , so as to release the movable parts s^{28} , s^{29} , s^{30} and s^{31} , respectively, and restore the 45 switch devices and their circuits to an inoperable condition. Each of these retaining devices is provided with an extension or projecting portion i^{28} , i^{29} , i^{30} and i^{31} , respectively, with which the inclined surfaces or 50 restoring devices c^{26} , c^{27} , c^{28} and c^{29} , respectively, engage to move portions t^{28} , t^{29} , t^{30} and t^{31} of such retaining devices out of engagement 55 with movable parts s^{28} , s^{29} , s^{30} and s^{31} , respectively, (when engaged therewith,) and restore their respective switch devices and circuits to an inoperable condition. Restoring device, c^{27} , in Fig. 14, is shown as 60 just about ready to engage with extension or projecting part i^{29} as such device is moving downward with carriage B^7 on which it is mounted. As restoring device c^{27} continues 65 its downward movement the inclined face of same comes in contact with the projection i^{29} and will force such projection inward and with it portion t^{29} , carrying the latter out of engagement with movable part s^{29} and releasing such part from the retaining

or holding action of retaining device T^{29} , and permitting such part to move into the position the corresponding part s^{28} is seen to occupy in Fig. 14, which corresponds to the position the part s^{31} occupies in Fig. 16.

In the construction shown in Figs. 14 to 17 each retaining device is separate from and movable independently of every other retaining device. The movement of any one of such devices cannot release any but its own movable part and restore its own switch device and circuit to an inoperable condition.

Each movable part has to be moved into position for its own retaining device to engage therewith and hold or retain it in operable condition and after this has occurred the restoring device adapted to engage with that particular retaining device can release it, as such restoring device moves past the retaining device.

The retaining device can only engage with the movable part when such part is moved by the segmental eccentric of that switch device as such eccentric moves in proper direction to close the circuit. When such eccentric moves in the other direction,

as it may move against the stress exerted by one of the arms of the two arm spring t^{31} for instance, such movement does not move the movable part, as s^{31} for instance. This movable part is moved only when the circuit is

closed and the switch device put into operable condition. Hence any movement of the retaining devices by the restoring devices at other times is of no practical effect on the movable parts of the switch devices

and such movements may take place without releasing such parts and restoring the switch devices to an inoperable condition. For this reason the restoring devices may be fixedly attached at desired points on the carriage

and there is no need of a portion being active and another portion inactive as the carriage moves in one direction, as is the case in the constructions seen in some of the preceding figures of the drawings, and all portions of the restoring devices may be active at all times.

The carriages are movable relatively to the retaining and switch devices in any well known manner, such for instance as indicated in Fig. 1, if desired, wherein rollers on studs or brackets guide and hold the carriage in proper relation to the parts with which they coöperate. Each controller is released, so that its spring, as P^2 , may move it

into position for the eccentric or eccentrics mounted thereon to be engaged by the first approaching coöperating rack moving in a direction to actuate its respective movable part, by means of a magnet, as O^1 , a circuit, a source of energy and a push button. The

push button will be located at any convenient point from where it is desired to signal the car, as for instance, one of the floors of the building which the apparatus is to serve, there being preferably twice as many con-

70

75

80

90

95

100

105

110

115

120

125

130

trollers, push buttons and magnets as there are floors or stations to be served, leaving out two of each, one for the top and one for the bottom floors, as only one controller, 5 push button and magnet is usually needed for these two floors, and these may, under some circumstances, be dispensed with and other devices be substituted therefor, if desired.

10 Each switch device is provided with a circuit connecting with a signal device, which may be operable for any given floor. This signal device is to be located in the car or elsewhere, where it is desired that the signals 15 shall be received. Each car may have its own signal device, circuits and switch devices, and there may be as many cars as desired, or each floor may have its own signal device or devices, &c., for each car. Each 20 controller may carry as many portions of switch devices as there are cars to be served, each switch device being operable independently of the others, so far as concerns the closing of the circuit, but each controller is 25 movable by any one of the segmental eccentrics of the switch devices mounted thereon. Hence, the first carriage that approaches a controller with the eccentrics of its switch devices in position to actuate its respective 30 movable parts engages with its respective eccentric and moves the controller, (with all of its switch devices,) away from all of the racks with which such other eccentrics are to coöperate and puts all of the switch devices on that controller in an inoperable condition until such controller is released again by operating its particular push button. In the construction thus shown the movable portions or members of the switch 35 devices are moved into position for the circuit or circuits connected therewith to be brought into an operable condition by the action of springs and such portions or members are moved into such positions to substantially the same extent when the segmental eccentrics are opposite their respective coöoperating racks as when such racks are in other portions of their movement, and, hence, the movement of such portions of the 45 switch devices is not interfered with by the movements of their coacting racks past the segments of eccentric gears mounted on the controllers. These controllers form means which connect two or more movable portions or members of the switch devices together and by which such portions or members may be moved simultaneously and the 50 circuits be brought into and out of an operable condition.

60 Signal device G^6 , diagrammatically indicated near the upper right hand corner of Fig. 14 is connected with switch devices coacting with carriage B^6 , and signal device G^7 is connected with switch devices coacting 65 with carriage B^7 , as is indicated in a similar

manner at the upper left hand corner of Fig. 14. The push buttons N^3 and N^4 , magnets O^1 and O^2 and source of energy D^4 are also in like manner indicated at the lower left hand corner of this Fig. 14. Source of energy D^5 for signal devices G^6 and G^7 is diagrammatically indicated just above the central portion of Fig. 14. Push button N^3 is connected to magnet O^1 and source D^4 by wires 66, 67 and 68 and push button N^4 is connected to magnet O^2 and source D^4 by wires 69, 67, 70 and 71. The signal device G^6 is connected with switch devices A^{30} , A^{32} , and source D^6 by suitable wires. Wire 72 leads from source D^5 to signal device G^6 from which wire 73 leads to contact spring a^{55} , which contacts with spring a^{54} having wire 74 leading to wire 75 which connects with the other side of source D^5 . Wire 73 also connects with wire 76 which connects a contact spring a^{58} which contacts with spring a^{59} which in turn connects with wires 74 and 75 and the other side of source D^5 .

Signal device G^7 is connected with switch devices A^{31} and A^{33} and source D^5 , as follows: Wire 77 leads from such source to such signal, from the signal a wire 78 leads to contact spring a^{60} and from contact spring a^{61} of this same switch device A^{33} a wire 75 leads back to source D^5 ; from wire 78 a wire 79 leads to contact spring a^{65} , and from contact spring a^{67} of this switch device A^{31} a wire 80 leads to wire 75 and thence to source D^5 . In this construction each circuit may be said to begin at one contact spring of each switch device and end with the companion contact spring of such device, passing through the signal device for that switch device on its way, that is, each circuit may be complete at all times, except at the switch device, where it is closed by the movement of the movable part mounted on its stud. By reason of this each circuit is practically independent of every other circuit and trouble on one circuit does not necessarily affect any other circuit, and there is little or no danger of cross circuiting in the apparatus. Also the contact springs have a rubbing contact on one another and cause a quick break in the circuit when they separate upon being released from the control of the movable part through the action of the retaining devices. The features in this construction shown in Figs. 14 to 17 not, in general, common with the constructions shown in preceding figures are not claimed herein, but form the subject matter of another application Serial No. 234,358, filed November 26, 1904.

The retaining devices may be constructed in various forms and yet be adapted to serve the same purposes in the same way in the combinations of devices herein described. Also different forms of restoring means may be employed to effect the restoration of the switch devices and connected circuits to an

inoperable condition. Also the construction of the individual switch devices may vary widely and yet such devices will be adapted to do the work done by any of the switch devices shown in the preceding figures of the drawings in the combinations of devices herein pointed out and each will do this work in the same way and without changing the mode of operation of the combinations or the manner of combining the devices together. For instance, the switch devices, instead of being constructed as shown in preceding figures, may be constructed as shown in Figs. 22 and 23 where each switch device consists of a movable part or controller carrying two terminals of a circuit mounted in a support fixed in position in the apparatus. This movable part, as shown in Fig. 23, is spring actuated in one direction by spring b^{40} and is actuated in the opposite direction by an elbow lever q^{40} , link r^{40} , armature s^{40} and electromagnet S^{40} , Fig. 22, which magnet is energized by any desired form of push button device and source of energy, in a manner similar to that shown in preceding figures of the drawings. Also instead of the retaining devices for two or more switch devices being made from one piece of material, so that such retaining devices move simultaneously they may be made out of separate pieces of material and connected together in any desired manner, for instance as seen in Figs. 22 and 24, and to connect with the switch devices and be actuated by the restoring means, carried on the carriage, as there shown. The switch devices A^{40} and A^{41} , as shown, are each provided with two terminals as a^{100} , a^{101} , a^{102} and a^{103} . These terminals of each switch device are made to contact, one with the other, by the engagement of the respective carriage therewith, as such carriage moves over and in engagement therewith, by pressing the terminal, as a^{100} into contact with terminal a^{101} and holding the two in contact, as seen in Fig. 24, until such carriage has passed on and the restoring devices, as c^{30} and c^{31} , carried by the carriage, have actuated the retaining device for that particular switch device, when such terminals are moved from the position seen in Fig. 24 to that which they occupy in Fig. 22, or are moved from an operative condition, as seen in Fig. 24, to an inoperative condition as seen in Fig. 22. The controller n^{40} , block m^{40} , and contact springs or terminals a^{100} and a^{101} form a movable portion or member of the switch device A^{40} . These contact springs or terminals a^{100} and a^{101} can yield when the carriage is in position over them and by reason of this the movable portion or member of the switch device is permitted to move to substantially the same extent when the carriage is in this position as when in other positions relatively to the switch device. These retaining devices, as T^{40} and

T^{41} , seen in Figs. 22 to 24 are pivotally mounted on their respective switch devices A^{40} and A^{41} and each is provided with an engaging part, as t^{40} and t^{41} , respectively, which engage with a projecting part or pin of the controller n^{40} , as shown, and prevents such controller from moving under the stress of the spring t^{40} until such retaining device or devices are moved by a restoring device carried by one of the carriages B^{10} or B^{11} . These retaining devices T^{40} and T^{41} are connected together, so as to move simultaneously, by a link L^{40} , which is spring actuated in one direction by a spring L^{41} . This spring tends to hold the retaining devices in position to engage with the controllers n^{40} and n^{41} whenever such controllers are moved into position where this engagement can take place.

In Fig. 22 the restoring device c^{31} is shown in engagement with the projecting portion i^{40} of retaining device T^{40} and has partially actuated the retaining device T^{40} from the position seen in Fig. 24, to that seen in Fig. 22, as such restoring device is moving past such retaining device. In Fig. 24 this restoring device c^{31} is shown in the position it occupies when the carriage B^{10} is moving in the opposite direction to that in which it is assumed to be moving in Fig. 22, and illustrates how such device may move past such retaining device without actuating the same, when such retaining device or devices are set to be actuated by a carriage moving in a direction opposite to that in which it or they are to be actuated, as hereinbefore explained in connection with Figs. 11 to 13, where the same kind of restoring devices are shown. The restoring devices are operated in the construction illustrated in Figs. 22 to 24 by means similar to what is shown in Figs. 11 to 13 and the description given in connection with these Figs. 11 to 13 will suffice, it is believed, for the construction shown in Figs. 22 to 24, there being a pivoted lever as Q^{10} , with a frictional connection between it and a bar, as Q^{12} and a pin and slot connection at the other end thereof with the restoring devices c^{30} and c^{31} , mounted on carriage B^{10} , which in turn is mounted to move in guides secured to the frame F^4 of the apparatus all as fully shown in Figs. 11 to 13. In this construction, as in preceding ones, there are circuits and switch devices normally in an inoperative condition, means adapted to bring such circuits and devices into operable condition, retaining means adapted to retain or hold such devices in such condition and restoring means adapted to restore such circuits and devices to an inoperative condition.

I have herein shown and described different embodiments of my invention wherein differing constructions of circuits, switch devices, retaining or holding means and re-

storing means, are to be found, each of which disclose combinations of devices or members in a signal apparatus or system having features common to all of the others.

- 5 In each construction shown the circuits are normally in an inoperable condition and they are brought into an operable condition by the movement of a part or member relatively to some other part or member which 10 is held or retained for the desired length of time, or during a desired extent of movement of another part or parts and is there moved more or less to restore such circuits to an inoperable condition.
- 15 In other applications of mine such as 234,357 and 284,358 modifications not herein specifically claimed, are more specifically claimed.

What is herein shown and described will 20 naturally suggest to the minds of those skilled in the art to which this invention pertains other constructions of parts and other arrangements thereof adapted to be combined together in the same way to accomplish equivalent work in substantially the same manner and, hence, I wish to be understood as including within the present invention all such constructions and combinations, having the mode of operation herein set forth and do not wish to be limited to the specific constructions or embodiments herein shown in the drawings.

The principle of my invention is in a measure explained in the following examples of what I believe I am the first to devise, which taken with the other descriptive matter and the drawings explain the best mode I have contemplated of applying that principle in an apparatus of the character herein referred to in which the signals for the different stations or floors are given by independently operable circuits normally in an inoperable condition, each circuit having a coacting portion or portions located at or near a common point movable into and out of operable condition or position at will, means movable relatively to such movable coacting portion or portions and coat therewith, when in operable condition, in giving signals and means for returning such circuits to their inoperable condition; also an apparatus in which the signals at the different stations or floors are given by independently operable circuits normally in an inoperable condition, each having a coacting portion or portions for closing its circuit movable into and out of operable condition or position, means adapted to bring each portion or portions into operable condition or position at will, retaining means to retain the circuits in operable condition for giving signals and separately acting means adapted to move each movable portion or portions from the operable to the inoperable condition or position when released from the retaining

means; also an apparatus in which the signals are given for the different stations or floors by independently operable circuits normally in an inoperable condition, each having a coacting movable portion movable 70 into and out of operable condition or position, independent means adapted to bring each portion or portions into operable condition or position, separately acting means adapted to move correspondingly as the elevator car moves and relatively to such circuits and their movable portions to operate the same, when in operable condition, for giving signals and restoring such circuits to their normal inoperable condition or positions; also an apparatus in which the signals are given by independently operable circuits normally in an inoperable condition, means adapted to bring a part coacting with each of such circuits into operable condition or 85 position, means adapted to retain each of such parts in operable condition and means adapted to move relatively to such parts and restore them to their inoperable condition or positions; also an apparatus in which the signal at each of the different stations or floors is given by a device in an independently operable circuit normally in an inoperable condition which is provided with a portion movable relatively to another portion 90 for giving the signal at its particular station or floor, a signal device movable relatively to the movable portions of the circuits, accordingly as the car moves, means adapted to bring each of such circuits into operable condition at will and means movable 95 relatively to the movable portions of the circuits accordingly as the car moves for giving the signals at the respective stations or floors; also an apparatus in which the signals are given by portions of circuits normally in an inoperative condition, each portion forming one member or terminal of a switch device which is movable into and out of operable condition, means adapted to 100 bring such member into operable condition at will and means adapted to move correspondingly as the car or other object moves for restoring such member or members to their inoperable condition after giving the signal or signals; also an apparatus in which the signals are given by circuits each of which is closed at all points but one and is provided with a portion normally in an inoperable condition, means which move it 105 from the operable to the inoperable condition, means adapted to hold or retain such portions in operable condition against the action of means which tend to move such portions out of operable condition; also an apparatus in which the signals are given by signal devices arranged in circuits normally in an inoperable condition, each having a portion movable into and out of operable condition by separately acting means, one of 110

which acts to move such portion into operable condition and the other to move it out of such condition and means adapted to hold or retain such portions in operable condition while the signals are being given; also an apparatus in which the movable portions of the circuits or switch devices are moved out of the operable condition by means other than the means which move relatively there-
10 to to actuate the signals and are retained in operable condition by means separate and distinct from the means which move such portion in either direction; also an apparatus in which separately acting means, as act-
15 tuating and restoring means are mounted to correspondingly move relatively to the movable portions of the circuits or switch devices, one of which actuates the signals and the other bodily moves a portion or por-
20 tions of separate and distinct means to restore such movable portions to an inopera-
ble condition.

What I claim as new is:—

1. In an elevator signaling apparatus in combination, two cars, a signal corresponding to each car; and, corresponding to each car, a normally-open circuit adapted when closed to operate the signal of that car and including a wire outside the car and stationarily located with respect to the movement of the car, a circuit-controlling part corresponding to a floor stationarily located with respect to the movement of the car, and a traveler moving correspondingly with its car and adapted to coöperate with said circuit-controlling part, when the latter is in its path, to close its signal circuit; both said circuit-controlling parts being normally out of the paths of said travelers, whereby they are normally ineffective to close the circuits, but each movable into the path of its traveler, a passenger's-button and means operable thereby to cause said circuit-controlling parts of both cars to move into the paths of the travelers, and a restoring device corresponding to each car, each operating to restore both the parts to their normal ineffective positions.

2. In an elevator signaling apparatus in combination, two cars, a signal corresponding to each car; and, corresponding to each car, a normally-open circuit adapted when closed to operate the signal of that car, a circuit-controlling part corresponding to a floor stationarily located with respect to the movement of the car, and a traveler moving correspondingly with but much slower than the car and adapted to coöperate with said circuit-controlling part, when the latter is in its path, to close its signal circuit; said circuit-controlling parts and travelers being compactly grouped together by themselves, both said circuit-controlling parts being normally out of the paths of

said travelers, whereby they are normally ineffective to close the circuits, but each movable into the path of its traveler, a passenger's-button and means operable thereby to cause said circuit-controlling parts of both cars to move into the paths of the travelers, and a restoring device correspond-
65 ing to each car, each operating to restore both the parts to their normal ineffective positions.

3. In an elevator-signaling apparatus in combination, two cars, a signal correspond-
75 ing to each floor for each car, a signal-con-
trolling part corresponding to each floor for each car stationarily located with respect to the movement of the cars; and for each car a traveler moved correspondingly with the car and adapted to coöperate in succession with its signal-controlling parts when the latter are in its path, to operate its signals successively; all the signal-con-
80 trolling parts being normally out of the paths of their travelers, whereby they are normally ineffective to operate the signals, but each movable into the path of its trav-
85 eler, a passenger's-button and means oper-
able thereby to cause said signal-controlling parts of both cars to move into the paths of the travelers, and a restoring device cor-
90 responding to each car and each restoring all the parts to their normal ineffective po-
95 sitions.

4. In an elevator-signaling apparatus in combination, two cars, a signal correspond-
100 ing to and located at each floor for each car, a signal-controlling part corresponding to each floor for each car stationarily located with respect to the movement of the cars; and for each car a traveler moved correspondingly with the car and adapted to coöperate in succession with its signal-
105 controlling parts when the latter are in its path, to operate its signals successively; all the signal-controlling parts being normally out of the paths of their travelers, whereby they are normally ineffective to operate the signals, but each movable into the path of its traveler, a passenger's-button and means operable thereby to cause said signal-con-
110 trolling parts to both cars to move into the paths of the travelers, and a restoring de-
115 vice corresponding to each car and each re-
storing all the parts to their normal in-
effective positions in succession, and means rendering each restoring device ineffective during a reverse movement of its car.

5. In an elevator-signaling apparatus in combination, two cars, a signal correspond-
120 ing to each car, a normally open circuit adapted when closed to operate the signal of one of said cars, a second normally open circuit adapted when closed to operate the signal of the other of said cars, circuit-con-
125 trolling parts corresponding to a floor and

- corresponding respectively to said cars and 5
stationarily located with respect to the
movement of said cars, travelers moving
correspondingly with the cars and adapted
5 to coöperate with said circuit-controlling
parts respectively when the latter are in the
paths of said travelers, to close said signal
circuits, a member controlling both of said
circuit-controlling parts which correspond
10 to a floor said member being normally in a
position to hold both said circuit-controlling
parts out of the paths of said travelers
whereby they are normally ineffective to
close the said circuits, a passenger's-button
15 and means operable thereby to cause said
member to move so as to bring said circuit-
controlling parts of both cars into the paths
of the travelers.
6. In an elevator-signaling apparatus in
20 combination, two cars, a signal correspond-
ing to each car, a normally-open circuit
adapted when closed to operate the signal
of one of said cars, a second normally-open
circuit adapted when closed to operate the
25 signal of the other of said cars, circuit-con-
trolling parts corresponding to a floor and
corresponding respectively to said cars and
stationarily located with respect to the
movement of said cars, travelers moving
30 correspondingly with the cars and adapted
to coöperate with said circuit-controlling
parts respectively when the latter are in the
paths of said travelers, to close said signal
circuits, a member controlling both of said
35 circuit-controlling parts which correspond
to a floor, said member being normally in a
position to hold both said circuit-control-
ling parts out of the paths of said travelers
whereby they are normally ineffective to
40 close the said circuits, a passenger's-button
and means operable thereby to cause said
member to move so as to bring said circuit-
controlling parts of both cars into the paths
of the travelers, and a restoring device cor-
45 responding to each car for restoring said
member to its normal position.
7. In an elevator-signaling apparatus in
50 combination, two cars, a signal correspond-
ing to each car, a normally-open circuit
adapted when closed to operate the signal
of one of said cars, a second normally-open
circuit adapted when closed to operate the
55 signal of the other of said cars, circuit-con-
trolling parts corresponding to a floor and
corresponding respectively to said cars and
stationarily located with respect to the
movement of said cars, travelers moving
60 correspondingly with the cars and adapted
to coöperate with said circuit-
controlling parts respectively when the
latter are in the paths of said travelers,
to close said signal circuits, a member con-
trolling both of said circuit-controlling
parts which correspond to a floor, said mem-
- ber being normally in a position to hold 65
both said circuit-controlling parts out of
the paths of said travelers whereby they are
normally ineffective to close the said circuits,
a passenger's-button and means operable
thereby to cause said member to move so as 70
to bring said circuit-controlling parts of
both cars into the paths of the travelers, and
retaining means for holding the said signal-
controlling parts in the set position.
8. In an elevator-signaling apparatus in 75
combination, two cars, a signal correspond-
ing to each car, a normally-open circuit
adapted when closed to operate the signal
of one of said cars, a second normally-open
circuit adapted when closed to operate the 80
signal of the other of said cars, circuit-con-
trolling parts corresponding to a floor and
corresponding respectively to said cars and
stationarily located with respect to the
movement of said cars, travelers moving 85
correspondingly with the cars and adapted
to coöperate with said circuit-controlling
parts respectively when the latter are in
the path of said travelers, to close said signal
circuits, a member controlling both of said 90
circuit-controlling parts which correspond
to a floor, said member being normally in a
position to hold both said circuit-control-
ling parts out of the paths of said travelers
whereby they are normally ineffective to 95
close the said circuits, a passenger's-button
and means operable thereby to cause said
member to move so as to bring said circuit-
controlling parts of both cars into the paths
of the travelers, retaining means for hold- 100
ing the said signal-controlling parts in the
set position, and means for reopening the
signal circuits.
9. In an elevator signaling apparatus in
105 combination, two cars, a signal at each floor
for each car, independent electric circuits
for the signals, means for operating the
same comprising for each floor movable sig-
nal-controlling mechanism normally ineffec-
tive but movable into position to cause the 110
signals of both cars to be given, means con-
trolling the movement of the same and com-
prising a passenger's-button at each floor;
and, for each floor, master mechanism
adapted to cause all the said signal-control-
ling mechanism for that floor to be restored
to normal position; a traveler for each car
moved correspondingly with but much
slower than that car and each adapted to
contact with and mechanically move said 120
master mechanisms in succession and there-
by cause all the said signal-controlling
mechanisms to be restored, said master
mechanisms and travelers being not carried
by the car but grouped together by them- 125.
selves.
10. In an elevator signaling apparatus in
combination, two cars, a signal at each floor

- for each car, independent electric circuits for the signals, means for operating the same comprising for each floor movable signal-controlling mechanism normally ineffective but movable into position to cause the signals of both cars to be given, means controlling the movement of the same and comprising a passenger's-button at each floor, and for each signal-controlling mechanism a magnet for setting the same and a circuit for the magnet closed by its corresponding passenger's-button; and, for each floor, master mechanism adapted to cause all the said signal-controlling mechanism for that floor to be restored to normal position; a traveler for each car moved correspondingly with but much slower than that car and each adapted to contact with and mechanically move said master mechanisms in succession and thereby cause all the said signal-controlling mechanisms to be restored, said master mechanisms and travelers being not carried by the car but grouped together by themselves.
11. In an elevator signaling apparatus in combination, two cars; and, for each car, a signal carried thereby and a signal at each floor, normally-open circuits adapted when closed to operate the signals corresponding to that car, a circuit-controller corresponding to each floor stationarily located with respect to the movement of the car, a traveler moving correspondingly with but much slower than the car and adapted to coöperate in succession with said signal-controllers, when the latter are in its path, to close its floor signal circuits successively and also operate the car signal; said circuit-controllers and travelers being grouped together by themselves, said circuit-controllers being normally out of the paths of said travelers, whereby they are normally ineffective to close the circuits, but each movable into the path of its traveler, and at each floor a passenger's-button and means operable thereby to cause the corresponding circuit-controllers of both cars to move into the paths of the travelers, and restoring mechanism corresponding to each car, each operating to restore the said circuit-controllers of both cars to their normal ineffective positions.
12. In an elevator signal apparatus in combination, a signal, a controlling circuit therefor having a circuit-controller adapted to close the circuit by two successive operations, means controlled at one or more floors for governing the first operation, a car, and means controlled by said car for governing the second operation of said circuit-controller, said circuit-controller being restorable to normal condition by the car's movement during the movement of the car in one direction only.
13. In elevator signaling apparatus in combination, a signal, a controlling circuit therefor having a circuit-controller adapted to close the circuit by two successive operations, means controlled at one or more floors for governing the first operation, a car, means controlled by said car for governing the second operation of said circuit-controller, another car, and means controlled by the other car for restoring said circuit-controller to normal condition.
14. In an elevator signaling apparatus in combination, a signal, a controlling circuit therefor having a circuit-controller adapted to close the circuit by two successive operations, means controlled at one or more floors for governing the first operation, a lock positively locking the circuit-controller in its signal-giving position, a car, and a traveler controlled by said car for governing the second operation of said circuit-controller, said circuit-controller being unlocked by the traveler and thereby restored to normal position during the movement of the car in one direction only.
15. In an elevator signal apparatus in combination, a plurality of cars, a passenger's button, a movable member, and means whereby said member is adapted to be displaced by the operation of said button, said movable member corresponding to the said button and corresponding to all the said cars in common, floor signal circuits including floor signals for indicating the direction of movement of said cars, and means moving correspondingly to said cars and coöperating with said movable member to close said floor signal circuits.
16. In an elevator signaling apparatus in combination, two cars, signals corresponding to each of the cars, circuits corresponding to each floor for operating the corresponding signals, a longitudinally movable bar corresponding to each floor controlling the signal circuits of both cars for that floor and normally rendering said signals inoperative, a passenger's-button at each floor and means controlled by said button for moving its bar to its signal-giving position, and means for restoring said bars to their normal positions in succession, said bars being grouped together by themselves.
17. In an elevator signaling apparatus in combination, two cars, signals corresponding to each of the cars, circuits corresponding to each floor for operating the corresponding signals, a longitudinally movable bar corresponding to each floor controlling the signal circuits of both cars for that floor and normally rendering said signals inoperative, a passenger's-button at each floor and means controlled by said button for moving its bar to its signal-giving position, and means for

restoring said bars to their normal positions in succession, said bars being grouped together by themselves, and each of said circuits having a single normally-open break

been moved through the operation of its passenger's button.
